Primary Examiner — Manpreet Matharu*Assistant Examiner* — Rebecca Tsehay(74) *Attorney, Agent, or Firm* — Wood Herron & Evans LLP(57) **CLAIM**

The ornamental design for a laboratory instrument, as shown and described.

DESCRIPTION

FIG. 1 is a front isometric view of our new laboratory instrument design;
 FIG. 2 is a bottom isometric view thereof;
 FIG. 3 is a top plan view thereof;
 FIG. 4 is a bottom plan view thereof;
 FIG. 5 is a front elevational view thereof;
 FIG. 6 is a rear elevational view thereof;
 FIG. 7 is a right side elevational view thereof; and,
 FIG. 8 is a left side elevational view thereof.
 The broken lines in FIG. 4 depict a portion of the laboratory instrument that forms no part of the claimed design.
